UNITED STATES PATENT OFFICE.

WALTER C. O'KANE, OF DURHAM, NEW HAMPSHIRE.

PASTE-SPREADING DEVICE.

1,170,181.

Specification of Letters Patent.

Patented Feb. 1, 1916.

Application filed January 22, 1914. Serial No. 813,785.

To all whom it may concern:

Be it known that I, WALTER C. O'KANE, a citizen of the United States, residing at Durham, in the county of Strafford and 5 State of New Hampshire, have invented a certain new and useful Improvement in Paste-Spreading Devices, of which the following is a specification.

The object of this invention is to provide 10 an improved device of the kind stated in which, among other advantages, economy, cleanliness and ease of operation are promoted.

The invention is embodied in the example 15 herein shown and described, the invention not being confined to precisely the forms of the parts shown.

In the accompanying drawings Figure 1 is a view in side elevation showing the 20 spreader attachment turned to operative position. Fig. 2 is a similar view showing the attachment moved to tube closing position. Fig. 3 is a similar view of the upper portion of the tube looking at the spreader 25 25 from the left hand side of Fig. 2. Fig. 4 is a plan view of the upper end of Fig. 1. Fig. 5 illustrates one purpose of the device and mode of using the same.

In the views 6 designates a tube of flexible metal having a rigid neck 6^a perforated 30 to afford an exit for the liquid, paste or other contents of the tube by pressure applied to the flexible walls of the tube. The neck or nozzle 6^a has hinged to it at 7, preferably by riveting the ends of the hinge pin, the spreader member 8. The spreader member 8 is formed with a curved portion 8^a that serves as a closure for the discharge end of the nozzle. The legs 8^b by means of 35 40 which the spreader and closure are connected with the nozzle are conveniently formed of the same piece as the spreader and closure. The hinging line of the spreader and closure is located at one side of the axis of the discharge opening in the nozzle and the end 45 of the nozzle is cut or formed on an arc concentric with said hinging line so that the general effect is a rounded beveling of the end of the nozzle. The closure portion 50 55 8^a is likewise formed on a like arc concentric with the axis of said hinging line so that the closure can be rocked from the open position, as shown in Fig. 1, to the position shown in Fig. 2, thereby effectively closing the discharge end of the nozzle. The spreader portion 8 is arranged at an acute

angle to the closure portion so as to form substantially a continuation of the bevel of the end of the nozzle when the spreader and closure are moved to open position, as 60 shown in Fig. 1. The free edge of the closure portion 8^a abuts against the shoulder at the top of the tube 6, as shown in Fig. 1, and so determines the operative position of the spreader.

This device is especially useful in the application of tooth paste to tooth brushes. The practice with this material is illustrated in Fig. 5 but it is also very serviceable in the application of adhesive paste. The 70 cover and spreader are first turned to the position shown in Fig. 1 and the tube held inclined and drawn with the spreader approximately flat upon the object to which the paste is to be applied. Just before or 75 simultaneously with the drawing of the spreader on the object the paste is squeezed from the tube by pressure in the quantity desired. After such a use the spreader is restored to the position shown in Fig. 1 to 80 close the discharge orifice and thereby prevent drying and hardening by evaporation of the paste left in the discharge orifice. Heretofore the discharge orifice of such a tube has commonly been closed with a threaded 85 cap which is oftentimes difficult and troublesome to turn on. With my device the orifice is either closed or opened by simple direct pressure applied with the finger or otherwise to the projecting spreader portion of the device.

What I claim is:

1. The combination with a paste container having a beveled discharge end, of a spreader loosely hinged to the container to form substantially a continuation of the beveled end.

2. The combination with a paste container having a discharge end, of a spreader loosely hinged to the container to lie, in use, beyond the discharge end, and a closure for the discharge moved with the spreader.

3. The combination with a paste container having a discharge end, of a spreader and a closure for the discharge end hinged thereto on an axis located at one side of the axis 105 of said discharge end, the discharge end being beveled at its extremity on an arc concentric with the axis of the hinge, and the closure being curved to substantially coincide with the beveled discharge end.

4. The combination with a paste container having a shoulder and a discharge end, of

a spreader and a closure for the discharge end hinged thereto on an axis located at one side of the axis of said discharge end, the discharge end at its extremity being formed on an arc concentric with the hinging axis, and the closure being curved to substantially coincide with the beveled dis-

charge end, the closure being extended to form a stop to engage said shoulder to hold the spreader in spreading position.

WALTER C. O'KANE.
